US00D948532S

(12) **United States Design Patent** (10) **Patent No.:** **US D948,532 S**
Johnson et al. (45) **Date of Patent:** **** Apr. 12, 2022**

(54) **DISPLAY SCREEN OR PORTION THEREOF
WITH GRAPHICAL USER INTERFACE**

(71) Applicant: **LIFE TECHNOLOGIES
CORPORATION**, Carlsbad, CA (US)

(72) Inventors: **Brian Johnson**, Rockton, IL (US); **Rachel Wihlborg**, Rockford, IL (US); **Kevin Abrams**, Loves Park, IL (US); **David Lu**, Austin, TX (US); **Todd Lefelt**, Los Angeles, CA (US); **Magdalena Wielopolski**, Los Angeles, CA (US); **Eve Songdej**, Los Angeles, CA (US); **Matthew Murray**, Los Angeles, CA (US); **Aron Wahl**, Los Angeles, CA (US); **Austin Beer**, Los Angeles, CA (US); **Charlie Hart**, Los Angeles, CA (US); **Agnes Won**, Los Angeles, CA (US); **Shane Nehring**, Oakland, CA (US)

(73) Assignee: **LIFE TECHNOLOGIES
CORPORATION**, Carlsbad, CA (US)

(**) Term: **15 Years**

(21) Appl. No.: **29/705,638**

(22) Filed: **Sep. 13, 2019**

Related U.S. Application Data

(62) Division of application No. 29/611,390, filed on Jul. 20, 2017, now Pat. No. Des. 864,982.

CLAIM

The ornamental design for a display screen or portion thereof with graphical user interface, as shown and described.

DESCRIPTION

FIG. 1 is a front view of a display screen or portion thereof with graphical user interface showing our new design; and, FIG. 2 is a front view of a second embodiment thereof. The outermost broken lines in the Figures show a display screen or portion thereof, and form no part of the claimed design. The other broken lines in the Figures show portions of the graphical user interface that form no part of the claimed design.
